WHALING HARPOON

Morris M. Marcus, Philadelphia, Pa., and Nils Gabrielsen, Brooklyn, N. Y.; said Marcus assignor of his interest to said Gabrielsen and said Gabrielsen assignor of his interest to said Marcus

Application September 11, 1945, Serial No. 615,528
In Canada July 11, 1946

10 Claims. (Cl. 102—48)

1

This invention relates to whaling harpoons and more particularly to improvements in the construction of that type of harpoon which is designed to be projected from a gun and is fitted with an explosive-charged head.

Heretofore and prior to the present invention, it has been the customary practice to provide the whaling harpoon with pivoted barb elements which are normally held in close-coupled relation to the shank of the harpoon until the instant the whale is struck. Upon striking the whale, the shock of the exploding charge in the head of the harpoon released the barb elements with respect to the harpoon shaft and caused them to swing radially thereof so as to become embedded in the body of the whale. The conventional construction of the harpoon, however, has been such that frequently the barb elements swing about their pivots to such extent that instead of extending more or less radially of the harpoon shaft they extend lengthwise thereof, with the result that their purchase in the body of the whale is so reduced that often the whale is enabled to free itself of the harpoon and is so lost to the whaler. Experience has taught that even if only one of the barbs is displaced from its proper radially extending position, the whale may be lost due to the fact that the harpoon head skews off in the body of the whale with consequent reduction in its ability to remain securely anchored in the whale body upon the application of the pulling effort on the harpoon against the weight of the harpooned whale. In addition, in this prior construction of the harpoon one or more of the pivot pins for the barb elements may be sheared off under the drag load of the harpooned whale with the result that they may be completely displaced from their supporting head, with consequent loss of the whale.

Also, it has been found that in order to accurately project the harpoon toward its target, the whale, it is necessary that the pointed explosive-charged head of the harpoon be maintained axially aligned with the harpoon shaft until the instant of impact, because in the absence of such alignment the harpoon tends to wobble in its flight and so does not travel true along the line of aim. In order to insure this axial alignment of the barbed head and its shaft, certain of the pivoted barbed elements are normally provided with hooked extremities which respectively interlockingly engage shouldered bosses formed on the forward extremity of the harpoon shaft. However, continued use of the harpoon eventually

ally causes such wear between these interlocking elements that they do not adequately hold the shaft and head in proper alignment, and it becomes necessary then to reshape either the interlocking hook of the barb element or the shouldered boss on the shaft, and sometimes both, in order to provide for proper engagement therebetween. Such reshaping is not always effective and often results in such damage to the barb elements or to the harpoon shaft as to require them to be completely discarded for further use.

The present invention has among its principal objects to so improve the construction of the harpoon as to obviate the difficulties and disadvantages above mentioned, a specific object being to provide a construction of the barbed element which cannot possibly swing about its pivot beyond a predetermined angle, the barbed element as constructed in accordance with the present invention including detent means which operate to positively limit the degree of its permissible swing outwardly of its support.

A further object is to provide the barb elements and their support with coacting means operative to retain the elements in anchoring position within the harpooned whale even though the pivot pins therefor be completely sheared off.

A further specific object of the present invention is to provide these barbed elements which engage the harpoon shaft to maintain the head and shaft of the harpoon in axial alignment during its flight toward the target with readily adjustable means for interlockingly engaging the shouldered bosses aforesaid. These means are preferably in the form of axially adjustable screws and are so designed that they may engage the said bosses with exactly the force required to hold the head in steady axial alignment with the harpoon shaft during flight of the harpoon and yet permit release of the barbed elements instantly upon explosion of the harpoon head in the body of the whale.

Other objects and advantages of the present invention will appear more fully hereinafter, it being understood that the present invention consists substantially in the combination, construction, location and relative arrangement of parts, all as will be described in detail hereinafter, as shown in the accompanying drawings and as finally pointed out in the appended claims.

In the said accompanying drawings, Figure 1 is a view, partially in elevation and partially in section, showing the head of the

harpoon and a portion of the shaft associated therewith;

Figure 2 is a similar view in elevation showing the assembly of Figure 1 as it appears when rotated through an angle of 90 degrees;

Figure 3 is an enlarged longitudinal sectional view of a portion of the assembly as shown in Figure 1;

Figure 4 is a sectional view taken on the line 4-4 of Figure 3;

Figure 5 is a transverse sectional view taken on the line 5-5 of Figure 3;

Figure 6 is a sectional view taken on the line 6-6 of Figure 3;

Figure 7 is an end elevational view of one of the barbed elements as viewed from the line 7-7 of Figure 1; and

Figure 8 is an enlarged partial sectional view of the screw-equipped end of the barbed element.

Referring now to the drawings and more particularly to Figures 1 and 2, it will be observed that the present invention relates to a whaling harpoon of the type having an elongated shank or shaft 10 provided at its forward end with an integrally formed coupling eye 11. This shank 10 of the harpoon is of conventional form, its main body being of cylindrical shape to fit within the bore of the conventional muzzle loading type of gun employed for projecting the harpoon toward its target. The cylindrical shank 10 of the harpoon is slotted as at 12 for receiving a slip-ring (not shown) to which is secured the retrieving line by means of which the harpooned whale may be drawn into the whaling vessel. The coupling eye 11 is provided upon opposite sides thereof with integrally formed bosses or lugs 13-13, each of which is provided with a flat seat 14, these seats being disposed in a plane extending transversely of the coupling eye 11 and normal to the longitudinal axis of the shank 10.

Coupled to the coupling eye 11 of the shank is the member 15 supporting a plurality of pivotally mounted barbed elements 16. The barb-supporting member 15 is provided with a front end portion 17 of generally cylindrical form and with a rear body portion 18 terminating a coupling eye 19, the coupling eye 19 being disposed at right angles to the coupling eye 11 and interlocked therewith, as shown in Figures 1, 2 and 3. It will be noted that the body portion 18 of the barb-supporting member 15 is of generally frustroconical shape to provide a supporting surface for the barbs 16, this supporting surface being outwardly flared rearwardly of the member 15.

The barbs 16 are preferably four in number spaced uniformly about their supporting member 15, and in their inoperative position these barbs normally assume relatively inclined positions shown in Figures 1 and 2.

The cylindrical body portion 17 of the member 15 is provided with four pairs of ears 20-20 uniformly spaced circumferentially about said cylindrical body 17. Each pair of said ears 20-20 receives therebetween the forward end of a barb 16, a pivot pin 21 being projected commonly through each pair of ears and the barb embraced therebetween to pivotally support the barb in position.

Referring now more particularly to Figure 3, it will be observed that each of the barbs 16 is provided at its forward pivoted end with a freely extending terminal element 22 which projects inwardly and toward the longitudinal axis of the supporting member 15 when the barb is in its

inoperative or collapsed position, shown in full lines in Figure 3. It will be noted also that the supporting member 15 for the barbs is provided with a pair of intersecting passages 23 and 24 therethrough, these passages being respectively in registry with the spaces formed between opposite sets of the paired ears 20-20. The intersecting passages 23 and 24 thus each extend entirely through the body portion 17 of the barb supporting member 15. The said member 15 is internally provided with a square depression 25 to provide a pocket, the cavity of which is in communication with the intersecting transverse passages 23 and 24. The depression 25 is so disposed in relation to the transverse passages 23 and 24 that when the barbs 16 are swung about their respective pivot pins 21 into their fully extended positions, as indicated by broken lines shown in Figure 3, the terminal elements 22 of the barbs 16 and so insure that the barbs will provide secure anchorages for the harpoon when its head is projected into and the cap exploded within the body of the whale.

A further important feature of this construction is that the terminal lugs 22 of the barbs 16 operate to engage the side wall portions 26 of the cavity 25 in the head 15 to lock the barbs in the head even in the event that the pivot pins are completely sheared through. In such case, the terminal lug 22 of a barb 16 whose pivot pin is sheared through engages the element 26 at the same time the outer edge 50 of the barb engages the forward wall of the transverse passage in which the barb is fitted, this being shown by dotted line representation in Figure 4.

As most clearly appears in Figures 1, 2 and 3, the pivoted barb elements 16 are so uniformly spaced about the member 15 as to provide two pairs thereof respectively disposed in intersecting planes, one pair of said barbs being disposed normally in the plane of the coupling eye 19 of the member 15 and the other pair being disposed normally in the plane of the coupling eye 11 of the shank or shaft 10. The barb elements 16 are all of the same length and of the same general configuration, each being provided at its outer extremity with an inwardly projecting hook element 27 forming a more or less acute angle with the main body portion of the barb element. The terminal ends of the hook-like elements 27 are preferably enlarged as at 28 and in the case of the barb elements which are disposed in the plane of the coupling eye 11, each of the enlarged terminal ends 28 is provided with a tapped hole 29 for reception of a set screw 30.

As most clearly appears in Figures 1 and 3, when the harpoon is initially made ready to be fired at the target, the barbed elements 16 are all swung into their collapsed position with one pair of the barbs respectively in engagement with the lugs or bosses 13 formed on either side of the coupling eye 11 of the shank 10. In this condition of the harpoon, the coupling eyes 11 and 19 are axially shifted toward each other so as to effect positive interengagement of the stud 51 formed on the end of the eye 11 with the socket 52 formed in the head 15 at the base of the coupling eye 19. This interengagement of the stud 51 and socket insures axial alignment of the shaft

and head of the harpoon. The barbed elements 16 which engage the lugs or bosses 13 are those which are provided with the axially adjustable screws 30 and these screws are tightened against the bosses 13 with sufficient force to secure and maintain the harpoon head 15 in axial alinement with the harpoon shaft 10.

It will be apparent that regardless of the extent of wear of the shouldered lugs 13-13, the set screw 30 may be adjusted to compensate for such wear and insure proper interlocking engagement between the barbs 16 and the coupling eye 11 of the shank. In order to prevent outward displacement of those barbs which are not interlocking engaged with the harpoon shaft during flight of the harpoon, it is customary to wrap a tie cord (not shown) about all of the barbs, this cord being readily broken by the shock of the explosion when the harpoon strikes its target. The shock of this explosion also releases the barbs 16 from their interlocking engagement with the lugs 13, so that all of the barbs are free to swing radially outwardly of their supporting body 15 and so securely anchor the harpoon within the body of the whale.

The harpoon of the present invention is provided with the conventional spear-headed cap 31, which is provided with an internal cavity 32 for receiving the explosive charge. This cap is threaded, as at 33, upon the forward end of the head 15, and the latter is provided with a longitudinal bore 34 (see Figure 3) into which is threaded a detonating fuse (not shown). Upon impact and explosion of the charge in the cap 31, the latter, is of course, shattered in the body of the whale and must be replaced by a new cap for each strike of the harpoon.

It will be understood, of course, that the present invention is susceptible of various changes and modifications which may be made from time to time without departing from the real spirit or principles thereof, and it is accordingly intended to claim same broadly, as well as specifically, as indicated in the appended claims.

What is claimed as new and useful is:

1. In a whaling harpoon of the character described having a shaft and a barb-carrying head linked thereto, said shaft being provided with a pair of oppositely projecting shoulders and said head being provided with a plurality of pivoted barbs, one pair of which are respectively provided at their free extremities with inwardly directed elements adapted to overlap said shoulders when the barbs are in collapsed position, said elements being each provided with adjustable screw means for effecting secure interengagement between said pair of barbs and said shoulders for maintaining said head and shank closely coupled and in axial alinement during flight of the harpoon.

2. In a whaling harpoon of the character defined in claim 1 wherein said shoulders are respectively provided with flat surfaces disposed in a common plane substantially normal to the longitudinal axis of the harpoon shaft, and wherein said adjustable screw means comprises an axially adjustable screw set in each shoulder-overlapping element of the pair of barbs aforesaid.

3. In a whaling harpoon of the character defined in claim 1 wherein said inwardly directed elements of the pair of barbs aforesaid are respectively provided with enlarged terminal ends fitted with axially adjustable set screws for en-

gaging the oppositely projecting shoulders on the shaft.

4. In a whaling harpoon of the character described having a shaft and a barb-carrying head linked thereto, said head being provided with intersecting passages extending therethrough at right angles to each other, barb elements respectively pivoted in the outer ends of each said passage, and coacting means formed on said barb elements and in said head to positively limit the maximum permissible outward swinging movement of the barb elements radially of the head, said last-mentioned means including an inwardly directed lug formed at the inner end of each barb element and lug-engaging movement-limiting flanges integrally formed within the harpoon head and extending in a direction axially forward thereof.

5. In a whaling harpoon of the character defined in claim 4 wherein said head is internally provided with a depression centered with respect to and opening into said intersecting passages to form solid wall parts respectively extending across the bottom of each passage, said solid wall parts constituting the lug-engaging flanges aforesaid, and wherein said barb elements are respectively provided at their pivoted ends with freely projecting terminal elements constituting the lugs aforesaid for respective engagement with said wall parts to limit the outward swinging movement of the barb elements.

6. In a whaling harpoon, an elongated shaft member, a barb-carrying head coupled thereto, a plurality of barbs pivoted to said head, oppositely projecting shoulders formed on said shaft member, and axially adjustable set screws respectively fitted in the outer free extremities of at least one pair of said barbs for engagement with said shoulders to securely maintain said head and shaft member in close coupled relation and in axial alinement during flight of the harpoon.

7. In a whaling harpoon, an elongated shaft member, a barb-carrying head coupled thereto, a plurality of barbs pivoted to said head and adapted to be outwardly swung from a collapsed inoperative position closely embracing said head into an open operative position extending substantially radially of said head, said head being provided with a transverse passage thereof for pivotally receiving therein the inner ends of a pair of opposed barbs and being further internally provided with a central cavity disposed rearwardly of the transverse plane of the pivoted axes of the barbs, said cavity having marginal portions extending in a direction axially of said barb carrying head and a terminal lug integrally formed on each of said barbs adapted to be shifted into said cavity for engagement with a marginal wall portion thereof when the barbs are swung outwardly into their open operative position, whereby to limit to a maximum permissible degree the outward swinging movement of the barbs.

8. In a whaling harpoon, a barb-carrying head having pivoted therein a plurality of barbs adapted to be outwardly swung from a collapsed inoperative position closely embracing said head into an open operative position extending substantially radially of the head, said barbs being characterised in that the pivoted ends thereof are each provided with a terminal lug extending laterally of the shank of the barb and toward the central longitudinal axis of the barb-carrying head, and detent means disposed rearwardly of the transverse plane of the pivotal axes of the

barbs for respective engagement by the terminal lugs of the barbs to limit their outward movement radially of the harpoon head.

9. In a whaling harpoon as defined in claim 8 wherein said detent means is in the form of a plurality of elements integral with said barb-carrying head and disposed respectively interiorly of the pivots of the several barbs.

10. In a whaling harpoon, a barb-carrying head having a plurality of barbs adapted to be swung from a collapsed inoperative position closely embracing said head into an open operative position extending substantially radially of the head, said barbs being characterised in that the inner ends thereof are each provided with a terminal lug extending laterally of the shank of the barb and toward the central longitudinal axis of said head, said head being provided with lateral slots for respective accommodation therein of the inner end portions of the several barbs, 20 each said slot being interiorly recessed to provide

detents extending axially of the barb-carrying head for locking engagement with the terminal lug of the barb when the latter is swung into open operative position.
